UNITED STATES PATENT OFFICE.

WILLIAM E. ELLIOTT AND DWIGHT S. COLE, OF GRAND RAPIDS, MICHIGAN; SAID COLE
ASSIGNOR TO SAID ELLIOTT.

HAND BUTTON-ATTACHING TOOL.

1,136,518.

Specification of Letters Patent. Patented Apr. 20, 1915.

Application filed May 9, 1913. Serial No. 766,555.

To all whom it may concern:

Be it known that we, WILLIAM E. ELLIOTT and DWIGHT S. COLE, citizens of the United States of America, residing at Grand Rapids, in the county of Kent and State of Michigan, have invented certain new and useful Improvements in Hand Button-Attaching Tools; and we do hereby declare the following to be a full, clear, and exact description of the invention, such as will enable others skilled in the art to which it appertains to make and use the same.

Our invention relates to improvements in hand button attaching tools, and more particularly to such tools adapted to attach shoe buttons and the like to leather or similar material by means of a metallic staple, and its object is to provide a device simple in construction and operation and which may be cheaply manufactured, to provide the tool with improved means for gripping and retaining the button and staple while it is being attached, and to provide the device with certain other new and useful features hereinafter more fully described and particularly pointed out in the claims, reference being had to the accompanying drawings, in which:—

Figure 1 is a plan view of a device embodying our invention; Fig. 2 is a vertical section of the same on the line 2—2 of Fig. 1; Fig. 3 is a vertical section of the jaws of the device illustrating the operation of clenching the button attaching staple; Fig. 4 shows the same before the clenching operation has commenced; Fig. 5 is an inverted sectional plan on the line 5—5 of Fig. 2; Fig. 6 is a transverse section through the points of the jaws taken on the line 6—6 of Fig. 3, and, Fig. 7 is a similar transverse section showing the jaws separated as in Fig. 4, and taken on the line 7—7 of said Fig. 4.

Like numbers refer to like parts in all of the figures.

This device is in the form of a hand plier consisting of two levers 1 and 2 crossed and pivoted together intermediate their ends, the shorter ends 1^a and 2^a serving as the jaws 50 of the plier, while opposite or longer ends serve as the handle members thereof. These lever members 1 and 2 are preferably formed of sheet metal stamped into the proper channeled shape, which enables them

to be made very cheaply. A spring 3 is 55 coiled about the pivot pin 4 of the plier, and its respective ends extend rearwardly and engage opposite handle members to normally retain the plier jaws in open position.

One of the jaws 2^a is adapted to receive 60 the button 7, together with the staple 8, and for that purpose it is provided with a short longitudinal slot 5 in its forward end, which is the proper size to receive the eye 7^a of the button, and the lower surface of the jaw is 65 provided with depressions 6 transverse of and adjacent to the said slot 5 adapted to receive the head of the staple 8. A retaining spring 9 extends above the upper surface of the jaw 2^a, and is provided in its forward 70 end with a longitudinal slot 9^a, corresponding and registering with the slot 5 in the said jaw. The forward end of this retaining spring is normally spaced away from the upper surface of the jaw but is adapted to 75 be pressed into engagement therewith, so that the eye of the button may be easily inserted into operative position in the slots 5 and 9^a after which the spring is released so that it may engage the under surface of the 80 button to raise the same and draw the head of the staple 8 snugly into the depressions 6 in the under surface of the jaw.

The retaining spring 9 is automatically depressed by a finger 12 which projects from 85 the handle lever 1 and engages the said spring when the jaws are wide open to press the same into engagement with the jaw 2^a but releases the said spring at the first 90 movement of closing the jaws.

The spring 9 extends backward from the point of the jaw 2^a toward the pivot of the plier and is looped and passed through an opening in the jaw of the plier, and its lower end extends along the under surface of the 95 said jaw toward the forward end thereof. The spring is attached by means of a screw 10, to the under surface of the jaw 2^a, and its lower end 11 extends forward to the transverse depression 6 and forms a stop 100 and guide shoulder to aid in adjusting the staple to its proper operative position. By looping the spring 9 and attaching it, as shown, to the under surface of the jaw, the loop of the spring is substantially in the 10 same plane with the slotted end of the jaw so that when the slotted end of the spring 9 rises away from the upper surface of the

jaw, this movement will be substantially vertical to the said end, thus raising the button in the desired direction and preventing it from moving outward in the slot.

5 The lower jaw 1^a forms the clenching die and is provided in its upper surface with two concave depressions 13 which the points of the attaching staple enter after passing through the stock 14 and as the points engage the inclined surfaces of the recesses they will be turned inward and thence, following the concave surfaces, upward again entering the leather, completely clenching the staple as shown in Fig. 6.

15 The principal advantages of this device, lie in the button retaining means. The usual form of construction in this type of device has been to attach a substantially flat spring to the upper side of the button holding jaw, and as such jaws were usually made of cast metal they were considerably thicker than the ones shown herewith, which brought the attaching point of the retaining spring considerably above the plane of the 20 end of the jaw, and consequently in rising away from the said jaw the end of the spring would also move outward, having a tendency to carry the eye of the button out of the slot in the jaw. This objectionable 25 feature has been entirely overcome in this invention by the form of the spring 9, and the location of the flexible portion of the same, for that, as the spring is released by the finger 12, it pulls the button directly upward drawing the staple firmly into the recesses 6 and against the stop and guide shoulder on the end 11 of the spring member, thus holding the staple firmly in place 30 in position to be driven, and furthermore, the construction has been simplified by utilizing the forward end of the lower fold of the spring as a stop shoulder, obviating the necessity and expense of forming such a shoulder on the jaw.

40 Copies of this patent may be obtained for five cents each, by addressing the "Commissioner of Patents, Washington, D. C."

What we claim is:—

1. A button attaching tool, comprising a pivoted jaw having an opening therethrough near its pivot to receive a spring and a slot in the end to receive the eye of a button, and a spring having a slot in the end registering with the slot in the jaw and extending through said opening in a curve and secured to the inner surface of the jaw, said spring also being freely movable in the opening, whereby the end of the spring moves substantially vertically to the end of the jaw. 50

2. A button setting tool, comprising a channeled sheet metal pivoted jaw having an opening near the pivot and provided at its outer end with a longitudinal slot to receive the eye of a button, and a spring above said jaw at one end and having a slot registering with the slot in the jaw, said spring also extending in a curve through the said opening and thence on the inner surface of 65 the jaw and secured thereto, the inner end of the spring also extending to a position opposite the slot in the jaw to engage and guide a staple.

3. A button attaching tool, comprising a 70 pivoted and channeled jaw having an opening near the pivot and adapted at its outer end to receive a button and staple and also provided near its pivot with an opening, and a spring bent to extend through said 75 opening and embracing the jaw, one end thereof being adapted to engage and lift a button away from the jaw and the other end secured to the under side of the jaw and adapted to engage and guide a staple. 80

In testimony whereof we affix our signatures in presence of two witnesses.

WILLIAM E. ELLIOTT.
DWIGHT S. COLE.
